UNITED STATES PATENT OFFICE

2,491,218

ACTION-LOCKING MEANS FOR SELF-LOADING FIREARMS

Harry H. Sefried, II, New Haven, Conn., assignor to Olin Industries, Inc., New Haven, Conn., a corporation of Delaware

Application January 17, 1947, Serial No. 722,675

9 Claims. (Cl. 42—21)

1

The present invention relates in general to firearms and more especially to that class of repeating firearms the breechblock and cartridge-loading mechanism of which are actuated automatically by gas-operated means supported beneath the barrel, the invention relating particularly to improved means for automatically locking the action open after the last cartridge in the magazine has been fired.

An object of the invention is to provide an improved action-locking means for firearms which is simple, convenient and reliable.

A further object of the invention is to provide a superior action-locking means which is capable of being readily applied to automatic self-loading firearms of the class referred to and which functions automatically to lock the action open after the last cartridge has been fired.

A still further object of the invention is to provide superior action-locking means for automatic self-loading firearms wherein a unitary carrier-latch member cooperatively engages a relatively-fixed abutment to automatically lock the action open when the last cartridge has been fired, the carrier-latch member being operable manually also for unlocking the action.

A still further object is to provide an improved carrier-latch for permitting one-hand loading.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a side elevation of a firearm embodying the present invention and which, for the purposes of illustration, is a gas-operated self-loading firearm having the compound-movement type of breechblock;

Fig. 2 is an enlarged broken view of a side elevation in section of the firearm shown in Fig. 1, the breechblock being locked in breech-closing position, and the hammer released for firing a cartridge in the chamber of the barrel;

Fig. 3 is a sectional elevation similar to Fig. 2 but with the action open, the breechblock being slightly forward of its rearmost position in the receiver and the hammer held thereby in its over-cocked position. In this view, the magazine is empty and no cartridge is supported on the carrier;

Fig. 4 is similar to Fig. 3 except that a cartridge is shown supported on the cartridge-carrier, as a

2

consequence of which the carrier-latch has been displaced out of engagement with the hammer;

Fig. 5 is a sectional elevation of the firearm on line 5—5 of Fig. 2 showing the position of the carrier-latch in the carrier;

Fig. 6 is a side elevation of the cartridge-carrier, including the improved carrier-latch of this invention;

Fig. 7 is a plan view of the carrier and carrier-latch shown in Fig. 6;

Fig. 8 is a perspective view of the carrier-latch; and

Fig. 9 is a perspective view of the hammer showing the latch-engaging tooth thereof.

15 For the purpose of illustrating one embodiment of the invention, an automatic self-loading firearm of the class having the so-called "compound movement" breechblock is used, the firearm, as shown in Fig. 1, comprising a receiver 10 having 20 a stock 11 secured to its rear end, and a barrel 12 and tubular magazine 13, furnished with the usual spring-loaded follower (not shown), secured to the forward end of the receiver, the tubular magazine 13 being suitably supported on the 25 underside of the barrel together with gas-operated mechanism indicated generally at 14, which is connected by an action-slide 15 to the breech-bolt for automatically moving the latter. To this end, the action-slide 15 extends rearwardly into 30 the receiver through a suitable guide-aperture in the front end thereof, the rear extremity of the action-slide 15 having an inwardly-projecting operating-lug 16 adapted to engage in a cam-slot 17 formed in the adjacent outer face of the breechblock 18, as shown in Figs. 2, 3 and 4, for reciprocating the latter longitudinally in the receiver and for raising and lowering the locking-nose 19 on the rear end of the breechblock into and from locking engagement with a locking-notch 20 formed in the solid top wall 21 of the receiver. A more complete disclosure of the above-described mechanism may be found in the Johnson Patent No. 958,407, dated May 17, 1910. An ejection-port 22 is provided in the right-hand 35 side of the receiver for ejecting spent cartridges therefrom, while the underside or bottom of the receiver comprises an open slot 23 closed at its rear end by a trigger-plate 24, the forward end of the slot 23 being left open to permit loading cartridges into the rear end of the tubular magazine 13.

40 The trigger-plate constitutes supporting-means for the firing-mechanism which comprises a hammer 25 mounted on a transverse pivot 26 and 45 formed with a cocking- or sear-shoulder 27

50

adapted to be engaged by the forward end or nose 280 of a sear 28, the latter being operatively associated with the trigger 29 which is pivotally mounted on the sear pivot-pin 30 in the trigger-plate. A small helical spring 31, suitably mounted in the trigger-plate 24, engages the rear end of the trigger 29 urging the forward end thereof to pivot upwardly. Mounted in the forward end of the trigger in cooperative engagement with the rear end of the sear 28, is a spring-loaded pilot 310 which urges the nose 280 of the sear upwardly for engagement with the sear-shoulder 27 of the pivoted hammer 25. The latter is provided, as usual, with a rearwardly-extending strut 32 constituting a guide-rod for a helical hammer-spring 33 which is carried thereon and which provides the striking force of the hammer.

The firing-mechanism may also embody suitable slide-action-bar locking-means and a hammer-engaging hook, as described more fully in the Johnson Patent No. 960,646, dated June 7, 1910, for preventing premature opening or firing of the gun, but inasmuch as these elements are non-essential to a full and clear disclosure of the present invention, a detailed description thereof is unnecessary here.

The hammer is adapted to be swung rearwardly to its cocked or hammer-spring loaded position by the breech-bolt 18 as the latter is moved rearwardly by the action-slide 15, the upper forward edge 34 of the hammer being slidably engaged by the underside 35 of the breechblock during the rearward excursion thereof. It is a characteristic of guns of this class that when the breechblock is at the end of its rearward excursion, the hammer is rotated rearwardly in a counterclockwise direction to a position such that its sear-shoulder 27 is carried forwardly out of engagement with the nose 280 of the sear 28, as shown clearly in Figs. 3 and 4, the distance between the nose of the sear and the sear-shoulder of the hammer being known as the "over travel" of the hammer. For purposes of the present description, this position of the hammer shall be hereinafter referred to as its "over-cocked" position and shall be understood to occur only when the breechblock is at or adjacent the end of its rearward excursion.

In addition to its function of cocking the hammer of the firearm, the reciprocating breechblock 18 is adapted to actuate a cartridge-carrier, indicated generally at 36. Referring to Figs. 6 and 7, the carrier comprises a lever-member 37 pivotally supported in the receiver on a transverse pin 38 and having a forwardly-extending reach or spoon 39 for the reception of cartridges which are adapted to be fed successfully thereon from the rear end of the tubular magazine 13 in the well known manner. The rear end of the lever-member 37 has an upwardly-and-rearwardly-extending arm 40 provided at its extremity with a spring-loaded inwardly-projecting cam-follower or plunger 41, the latter being adapted to cooperatively engage a suitable cam-surface indicated generally at 42 on the inside wall of the breechblock for actuating the cartridge-carrier during the forward excursion of the breechblock. A more detailed description of these features of this class of firearm may be found in the Johnson Patent No. 959,016, dated May 24, 1910, but for purposes of this disclosure it will suffice to say that the cam-surface 42 of the breechblock coacts with the cam-follower 41 of the carrier in what is known by mechanics as "island move-

ment," whereby as the breechblock moves rearwardly from breech-closing position, the cam-follower 41 is depressed by engagement with the adjacent side wall of the breechblock out of the path of travel of the latter so that it may move rearwardly freely without actuating the carrier. However, when the breechblock reaches the end of its rearward excursion, the cam-follower 41 snaps into engagement with the cam-surface 42 of the breechblock and more particularly a downwardly-and-rearwardly-extending shoulder 43 thereof, so that on the forward movement of the breechblock, the arm 40 of the carrier will be positively depressed and its forwardly-extending spoon 39 elevated, whereby a cartridge thereon will be lifted into position to be pushed into the breech- or cartridge-chamber 44 of the barrel by the forward end of the breechblock, the spoon of the carrier being maintained in its upper position until the cartridge has been sufficiently entered into the chamber to provide for full control thereof. After the cam-follower 41 has been disengaged from the underside of the forwardly-moving breechblock, a carrier-spring 45, in engagement with the carrier-arm 40, rotates the carrier clockwise so as to lower its spoon 39 into its original cartridge-receiving position.

As pointed out above and as shown in the drawings, the coaction of the downwardly-and-rearwardly-extending cam-shoulder 43 of the breechblock and the cam-follower 41 of the pivoted carrier is such that the spoon 39 of the latter is cammed upwardly positively as the breechblock begins its forward excursion from breech-open position. Conversely, if the carrier-spoon 39 is positively held from swinging upwardly, the coaction of the cam-shoulder 43 of the breechblock and the cam-follower 41 of the carrier constitutes a jamming action which will suffice to prevent the breechblock from moving forwardly, the latter being, in effect, locked in breech-open position.

The present invention relates to improved breechblock-locking means carried by the cartridge-carrier and adapted to engage a relatively-fixed abutment to prevent the upward swinging movement of the carrier-spoon when there is no cartridge thereon, and to thereby lock the breechblock in its retracted or breech-open position each time the magazine of the firearm is emptied.

Referring to Figs. 6, 7 and 8, the breechblock-locking means of the invention comprises a carrier-latch indicated generally at 46, pivotally supported by a transverse pin 47 in a rectangular slot 48 intersecting the rear end of the carrier-spoon and forwardly the pivot 38 thereof, the latch being disposed in a vertical plane coincident with the vertical plane of the hammer 25 and extending substantially along the longitudinal axis of the carrier-spoon 39, as shown in Figs. 5, 6 and 7. The upper end of the latch is formed with an integral upwardly-and-forwardly-projecting lug which is slotted vertically to provide two spaced parallel fingers 49, the tips 50 of which are adapted normally to be held forwardly resiliently in the path of a cartridge being delivered onto the carrier-spoon 39 from the magazine 13 by the force of a latch-spring 51. The latter comprises a coil-spring supported on the latch-pivot pin 47 in the slot between the spaced fingers 49, the leg 52 of the spring extending downwardly into a recess 53 in the forward face of the latch, as shown in Fig. 6, the other leg 54 of the spring

bearing against the underside of the carrier-spoon as, for instance, after the last cartridge in the magazine has been fired, the fingers 49 of the latch are free to swing forwardly and are resiliently held in a forward position by the force of the latch-spring 51, the forward position of the fingers 49 being hereinafter referred to as the "operating position" of the latch. If, on the other hand, a cartridge is delivered from the magazine onto the spoon of the carrier, the rearwardly-moving head of the cartridge is adapted to engage the tips 50 of the latch-fingers 49 and rotate the latter rearwardly in a counterclockwise direction, the rearward position of the fingers being hereinafter referred to as the "inoperative" position of the latch.

As shown in Figs. 2, 3, 4 and 6, the lower end of the pivoted latch 46 extends downwardly below the underside of the carrier and is provided with a rearwardly-extending tooth 55 which is adapted, in a preferred embodiment of the invention, to engage a tooth 56 formed on the hub-portion of the hammer 25. To this end, the hammer-tooth 56 is located on the hub of the hammer forwardly of the sear-shoulder 27, so that when the latch-fingers 49 are in their forward latch-operating position and the hammer 25 has been swung counterclockwise to its over-cocked position, the tooth 56 of the hammer will be moved above the latch-tooth 55 and substantially in line with the path of movement thereof. Moreover, it will be apparent that when the hammer 25 is in its over-cocked position, pivotal movement thereof in a clockwise direction is positively prevented by engagement of the forward edge 34 of the hammer with the underside 35 of the breech-bolt, which, as shown, is at the end of its rearward excursion. The tooth 56 of the hammer constitutes, in effect, therefore, a relatively-fixed abutment. Consequently, as the breech-block begins to move forwardly from its rearmost position in the receiver, the downwardly-and-rearwardly-sloping cam-shoulder 43 of the breechblock engages the cam-follower 41 of the carrier and starts to depress the rearwardly-extending arm 40 and hence to elevate the carrier-spoon 39 and latch 46. In so doing, however, the latch-tooth 55 is brought up into locking engagement with the hammer-tooth 56 whereby further upward swinging movement of the carrier is prevented; and since the carrier is thus positively held from further movement upwardly, the cam-shoulder 43 of the breechblock jams against the immovable cam-follower 41 of the carrier-arm 40, whereby the breechblock is effectively locked in breech-open position.

It may also be pointed out that the provision of the carrier-latch tooth on the hammer serves not only to lock the action open each time the magazine is emptied, as hereinafter described, but also insures disengagement of the carrier-latch from the hammer-tooth whenever the hammer is in any position other than its over-cocked position. That is to say, when the action is closed and the hammer is in either its cocked or firing position, the carrier is unlatched and free to swing upwardly so that the magazine may be loaded with one hand and with ease.

The breechblock is adapted to be unlocked manually and to this end, the lower end of the latch is provided with a finger-piece 57 for pivoting the latch-tooth 55 out of engagement with the tooth 56 of the hammer, so as to free the carrier and permit the latter to rotate upwardly

about its pivot, thereby releasing the breechblock and permitting it to be moved forwardly by the force of the compressed action-operating spring 58, see Fig. 1, to breech-closing position.

In the normal operation of the firearm, cartridges will be delivered successively from the magazine onto the spoon 39 of the cartridge-carrier, the head of each cartridge moving rearwardly into engagement with the fingers 49 of the latch so as to hold the latch in its inoperative position and thus permit the carrier to be rotated freely about its pivot by coaction with the forwardly-moving breechblock and to elevate the cartridge on the carrier into the breech of the barrel. After the last cartridge has been delivered from the magazine and fired, the breechblock will be moved rearwardly by the gas-operated action-slide mechanism 14 to eject the fired cartridge. As the breechblock approaches the end of its rearward excursion, the hammer 25 is pivoted counterclockwise to its over-cocked position, thereby moving its tooth 56 into position for engagement with the carrier-latch tooth 55, which is now in its operative position, as the carrier starts to swing upwardly, as a consequence of which the carrier is positively held from further movement and the cam-shoulder 43 of the breechblock jams against the immovable cam-follower 41, the breechblock being held thereby in its retracted breech-open position.

Although the invention is incorporated in a firearm having a gas-operated slide-action operating-mechanism, it will be understood that the invention may be used on firearms having mechanical and other equivalent means for automatically operating the breechblock. Moreover, the improved breechblock-locking means is of simple but rugged construction, of relatively-few parts and conveniently accessible for both automatic and manual operation.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A firearm, including in combination: a receiver; a barrel carried by said receiver; a breechblock movably mounted in said receiver; means 55 to move said breechblock to and from breech-closing position; a relatively-fixed abutment in said receiver; cartridge-feed means including a movable cartridge-carrier for delivering a cartridge into the breech of said barrel, said carrier 60 and breechblock having mutually-engageable surfaces constructed and arranged to coact so as to permit said breechblock to move forwardly freely with respect to said carrier into breech-closing position when said carrier is free to move 65 and to hold said breechblock immobile at the end of its rearward excursion in said receiver when said carrier is held from moving; and cartridge-actuated breechblock-locking means mounted on said cartridge-carrier forwardly of 70 said relatively-fixed abutment, said locking-means being constructed and arranged to engage said relatively-fixed abutment in the absence of a cartridge on said carrier to hold said carrier from moving and thereby to lock said breechblock 75 in breech-open position.

2. A firearm, including in combination: a receiver; a barrel carried by said receiver; a breechblock movably mounted in said receiver; means to move said breechblock to and from breech-closing position; a relatively-fixed abutment in said receiver; cartridge-feed means including a movable cartridge-carrier for elevating a cartridge into the breech of said barrel, said carrier and breechblock having mutually-engageable surfaces constructed and arranged to permit said breechblock to move forwardly freely with respect to said carrier into breech-closing position when said carrier is free to move and to hold said breechblock immobile at the end of its rearward excursion in said receiver when said carrier is held from moving; and cartridge-actuated breechblock-locking means comprising a latch pivotally mounted on said cartridge-carrier forwardly of said relatively-fixed abutment and a resilient member arranged normally to engage and urge said latch into position for engagement with said relatively-fixed abutment in the absence of a cartridge on said carrier thereby to hold said carrier from moving and lock said breechblock in breech-open position.

3. A firearm, including in combination: a receiver; a barrel carried by said receiver; a breechblock movably mounted in said receiver; means to move said breechblock to and from breech-closing position; a relatively fixed abutment in said receiver; cartridge-feed means including a movable cartridge-carrier for delivering a cartridge into the breech of said barrel, said carrier and breechblock having mutually-engageable surfaces constructed and arranged to permit said breechblock to move forwardly freely with respect to said carrier into breech-closing position when said carrier is free to move and to hold said breechblock immobile at the end of its rearward excursion in said receiver when said carrier is held from moving; a cartridge-actuated breechblock-locking means comprising a latch pivotally mounted on said cartridge-carrier forwardly of said relatively-fixed abutment and a spring carried by said carrier and arranged normally to coat therewith and with said latch to urge said latch into position for engagement with said relatively-fixed abutment in the absence of a cartridge on said carrier thereby to hold said carrier from moving and lock said breechblock in breech-open position; and a finger on said latch arranged to be engaged by a cartridge on said carrier automatically to render said latch inoperative.

4. A firearm, including in combination: a receiver; a barrel carried by said receiver; a breechblock movably mounted in said receiver; means to move said breechblock to and from breech-closing position; firing-mechanism comprising a hammer having a projection thereon; cartridge-feed means including a movable cartridge-carrier for elevating a cartridge into the breech of said barrel, said carrier and breechblock having mutually-engageable surfaces constructed and arranged to permit said breechblock to move forwardly freely with respect to said carrier into breech-closing position when said carrier is free to move and to hold said breechblock immobile at the end of its rearward excursion when said carrier is held from moving; and breechblock-locking means comprising a pivoted latch carried by said cartridge-carrier and a spring arranged normally to urge said latch into position for engagement with the projection of said hammer in the absence of a cartridge on said carrier thereby to hold said

carrier from moving and lock said breechblock in breech-open position.

5. A firearm, including in combination: a receiver; a barrel carried by said receiver; a breechblock movably mounted in said receiver; means to move said breechblock to and from breech-closing position; firing-mechanism comprising a pivoted hammer having a projecting tooth, said hammer being arranged to be moved and held in over-cocked position by the rearward excursion of said breechblock; cartridge-feed means including a pivoted cartridge-carrier for elevating a cartridge into the breech of said barrel, said carrier and breechblock having mutually-engageable surfaces constructed and arranged to permit said breechblock to move forwardly freely with respect to said carrier into breech-closing position when said carrier is free to move and to hold said breechblock immobile at the end of its rearward excursion when said carrier is held from moving; and breechblock-locking means comprising a pivoted latch carried by said cartridge-carrier, and a spring arranged normally to urge said latch into position for engagement with the tooth of said pivoted hammer when said hammer is held in its over-cocked position, and in the absence of a cartridge on said carrier thereby to hold said carrier from moving and lock said breechblock in breech-open position.

6. A firearm, including in combination: a receiver; a barrel carried by said receiver; a breechblock movably mounted in said receiver, said breechblock having a cam-shoulder; automatic means to move said breechblock to and from breech-closing position; firing-mechanism comprising a pivoted hammer having a tooth, said hammer being arranged to be moved and held in over-cocked position by the rearward excursion of said breechblock; cartridge-feed means including a pivoted cartridge-carrier for elevating a cartridge into the breech of said barrel, said carrier having a rearwardly-extending arm provided with a cam-follower adapted to engage the cam-shoulder of said breechblock, said cam-follower and cam-shoulder being arranged to coat so as to permit said breechblock to move forwardly freely into breech-closing position when said carrier is free to pivot upwardly but to hold said breechblock immobile at the end of its rearward excursion when said carrier is held from pivoting upwardly; and breechblock-locking means comprising a pivoted latch carried by said cartridge-carrier and a spring arranged normally to urge said latch into position for engagement with the tooth of said pivoted hammer when said hammer is held in its over-cocked position and in the absence of a cartridge on said carrier thereby to hold said carrier from moving and lock said breechblock in breech-open position.

60. A firearm, including in combination: a receiver, a barrel carried by said receiver; a breechblock movably mounted in said receiver, said breechblock having a cam-shoulder; automatic means to move said breechblock to and from breech-closing position; firing-mechanism comprising a pivoted hammer having a tooth, said hammer being arranged to be moved and held in over-cocked position by the rearward excursion of said breechblock; cartridge-feed means including a pivoted cartridge-carrier for elevating a cartridge into the breech of said barrel, said carrier having a rearwardly-extending arm provided with a cam-follower adapted to engage the cam-shoulder of said breechblock, said cam-follower and cam-shoulder being arranged to coat

so as to permit said breechblock to move forwardly freely into breech-closing position when said carrier is free to pivot upwardly but to hold said breechblock immobile at the end of its rearward excursion when said carrier is held from pivoting upwardly; breechblock-locking means comprising a pivoted latch carried by said cartridge-carrier and a spring arranged normally to urge said latch into position for engagement with the tooth of said pivoted hammer when said hammer is held in its over-cocked position and in the absence of a cartridge on said carrier thereby to hold said carrier from moving and lock said breechblock in breech-open position; and a finger on said latch projecting upwardly in said carrier and arranged to be engaged by a cartridge thereon automatically to pivot said latch out of its position for engagement with the said hammer-tooth to enable said carrier to pivot upwardly and hence permit forward excursion of said breechblock.

8. A firearm, including in combination: a receiver; a barrel carried by said receiver; a breechblock movably mounted in said receiver, said breechblock having a cam-shoulder; automatic means to move said breechblock to and from breech-closing position; firing-mechanism comprising a pivoted hammer having a tooth, said hammer being arranged to be moved and held in over-cocked position by the rearward excursion of said breechblock; cartridge-feed means including a pivoted cartridge-carrier for elevating a cartridge into the breech of said barrel, said carrier having a rearwardly-extending arm provided with a cam-follower adapted to engage the cam-shoulder of said breechblock, said cam-follower and cam-shoulder being arranged to coact so as to permit said breechblock to move forwardly freely into breech-closing position when said carrier is free to pivot upwardly but to hold said breechblock immobile at the end of its rearward excursion when said carrier is held from pivoting upwardly; breechblock-locking means comprising a pivoted latch carried by said cartridge-carrier and a spring arranged normally to urge said latch into position for engagement with the tooth of said pivoted hammer when said hammer is held in its over-cocked position and in the absence of a cartridge on said carrier thereby to hold said carrier from moving and lock said breechblock in breech-open position; and a finger-piece pro-

jecting downwardly from said latch for manually disengaging said latch from said hammer.

9. A firearm, including in combination: a receiver; a barrel carried by said receiver; a breechblock movably mounted in said receiver, said breechblock having a cam-shoulder; gas-operated means to move said breechblock to and from breech-closing position; firing-mechanism comprising a pivoted hammer having a tooth, said hammer being arranged to be moved and held in over-cocked position by the rearward excursion of said breechblock; cartridge-feed means including a pivoted cartridge-carrier for elevating a cartridge into the breech of said barrel, said carrier having a rearwardly-extending arm provided with a cam-follower arranged to engage the cam-shoulder of said breechblock, said cam-follower and cam-shoulder being arranged to coact so as to permit said breechblock to move forwardly freely into breech-closing position when said carrier is free to pivot upwardly but to hold said breechblock immobile at the end of its rearward excursion when said carrier is held from pivoting upwardly; breechblock-locking means comprising a pivoted latch carried by said cartridge-carrier and a spring arranged normally to urge said latch into position for engagement with the tooth of said pivoted hammer when said hammer is held in its over-cocked position and in the absence of a cartridge on said carrier thereby to hold said carrier from moving and lock said breechblock in breech-open position; a finger on said latch projecting upwardly in said carrier and arranged to be engaged by a cartridge thereon automatically to pivot said latch out of its position for engagement with the said hammer-tooth to enable said carrier to pivot upwardly and hence permit forward excursion of said breechblock; and a finger-piece projecting downwardly from said latch for manually disengaging said latch from said hammer.
